UNITED STATES PATENT OFFICE

160,874

TOY ANIMAL FIGURE

Ann N. Marshall, Taos, N. Mex.

Application June 10, 1949, Serial No. 3,200

Term of patent 3½ years

(Cl. D34—2)

To all whom it may concern:

Be it known that I, Ann N. Marshall, a citizen of the United States, residing at Taos, State of New Mexico, have invented a new, original, and ornamental Design for a Toy Animal Figure, of which the following is a specification, reference being had to the accompanying drawing, forming a part hereof.

The essential features of my design are shown in full lines.

I claim:

The ornamental design for a toy animal figure, as shown and described.

ANN N. MARSHALL.
